AUDION ARRANGEMENT FOR SHORT WAVE
TELEVISION PURPOSES

Kurt Schlesinger, Berlin, Germany

Application July 17, 1934, Serial No. 735,600
In Germany July 19, 1933

4 Claims. (Cl. 250—27)

In the patent application Ser. No. 717,310 there is described an audion arrangement for short-wave and more particularly television purposes, which at the same time causes compensation of the carrier frequency.

It has been found that this arrangement transmits the width of band necessary for television purposes merely in incomplete fashion.

The subject matter of the present invention is an additional development of the arrangement set forth in application 717,310, which completely avoids the stated disadvantage.

According to the invention, the circuit linked up with the two control grids of the audion is damped to such extent, preferably by the use of resistances as poor in capacity as possible, that the same no longer reveals any kind of oscillatory properties.

The secondary coil, according to the invention, is so dimensioned that its natural oscillation is in the vicinity of the unmodulated carrier wave.

A form of embodiment of the arrangement according to the invention is illustrated by way of example in the drawing.

In the same

1 is the final stage of the intermediate frequency amplifier with the primary coil 2, 3 the secondary coil, which is earthed at the centre and is preferably dimensioned in such fashion that its natural oscillation period is situated in the vicinity of the unmodulated carrier wave (for example approximately 150 metres), 6 and 7 are the audion condensers, which in accordance with application 717,310 are preferably very small, for example are each selected at approximately 3 cm., 8 and 9 the grid leak resistances, which may have a size of .1 megohm, 10 is the audion tube with the cathode 13, the two control grids 11 and 12, which are preferably passed out separately, the screening grid 14 and the anode 15, and 4 and 5 are the two damping resistances employed in accordance with the invention for damping the circuit, which are as poor in capacity as possible and may each have a size of 10^4 ohms.

The anode and screening potential grid are supplied by a battery 16 which however may be substituted by a main supply apparatus and

which may be separate for each of the valves 1 and 10.

I claim:

1. An audion arrangement for grid-detection, more particularly in the case of television signals modulated on a carrier frequency comprising a transformer coupled to the output of a carrier frequency amplifier, the secondary of said transformer being tuned by its natural capacities to said unmodulated carrier frequency, a multi-electrode valve at least comprising an anode, a cathode, and two control grids, said cathode being connected to earth, two audion condensers, the middle tapping point of said secondary connected to earth, the ends of said secondary connected by way of said condensers to said control grids, two leak resistances each connected between one of said grids and earth and two damping resistances each connected between the one end of said secondary and earth across the two halves of said secondary.

2. An audion arrangement for grid-detection, more particularly in the case of television signals modulated on a carrier frequency comprising a transformer coupled to the output of a carrier frequency amplifier, the secondary of said transformer being tuned by its natural capacities to said unmodulated carrier frequency, a multi-electrode valve comprising an anode, a cathode, and a screen grid, two control grids, said cathode being connected to earth, two audion condensers, the middle tapping point of said secondary connected to earth, the ends of said secondary connected by way of said condensers to said control grids, two grid resistances each connected between one of said grids and earth and two damping resistances each connected between the one end of said secondary and earth across the two halves of said secondary, said damping resistances being so dimensioned as to prevent oscillatory properties.

3. An audion arrangement according to claim 2, characterized in that the damping resistances are selected at approximately $\frac{1}{10}$ of the grid leak resistances.

4. An audion arrangement according to claim 2, characterized in that the damping resistances are selected in the order of 10^4 ohms.

KURT SCHLESINGER.
